UNITED STATES PATENT OFFICE.

MATHEW M. MORATTA, OF PRINCETON, INDIANA.

PISTON RING.

Application filed June 22, 1923, Serial No. 647,069. Renewed March 31, 1926.

This invention relates to packing rings for use in engines and in all devices in which rings are necessary and has for its principal object to provide a device of this nature which will take up the wear in the piston ring groove.

Another important object of the invention is to provide a device of this nature having a comparatively simple and efficient construction, one which is reliable in use, inexpensive to manufacture, durable, and well adapted to the purpose for which it is designed.

With the above and numerous other objects in view as will appear as the description progresses the invention resides in certain novel features of construction, and in the combination and arrangement of parts as will be hereinafter more fully described and claimed.

In the drawing:

Figure 1 is an edge elevation of the device embodying my invention.

Figure 2 is a section therethrough taken substantially on the line 2—2 of Figure 5.

Figure 3 is a section taken substantially on the line 3—3 of Figure 1.

Figure 4 is a section taken substantially on the line 4—4 of Figure 1, and

Figure 5 is an edge elevation of the ring taken at right angles to the view shown in Figure 1.

Referring to the drawing in detail it will be seen that the ring is split longitudinally and transversely so as to form a pair of di-

verging fingers 1 and a second pair 2. These fingers 1 and 2 extend from the body 3. The upper fingers of each pair terminate adjacent each other as do the lower fingers of each pair. The upper fingers of each pair are curved away from the lower fingers. The terminals of the upper fingers are offset from the terminals of the lower fingers as is clearly shown in Figure 5.

Having thus described my invention what I claim as new is:

1. A piston ring of the class described being split longitudinally and transversely to form two pair of fingers, the fingers in each pair diverging from each other.

2. A piston ring of the class described including a body of curved structure, a pair of diverging fingers extending from one side of the body and curved throughout their length, and a similar pair of fingers extending from the other side of the body, the upper fingers of the two pairs of fingers terminating at a point offset from the point of termination of the lower fingers.

3. A piston ring of the class described including a body of curved structure, a pair of diverging fingers extending from one side of the body and curved throughout their length and a similar pair of fingers extending from the other side of the body, the upper fingers of the two pairs of fingers terminating adjacent each other offset from the terminations of the lower fingers.

In testimony whereof I affix my signature.

MATHEW M. MORATTA.
